[57] CLAIM

The ornamental design for an under-the-cabinet-coffeemaker, as shown and described.

DESCRIPTION

FIG. 1 is a perspective view of the under-the-counter-coffeemaker taken from the front, right and top sides thereof, illustrating my new design;

FIG. 2 is a front elevational view thereof;

FIG. 3 is a right side elevational view thereof;

FIG. 4 is a bottom plan view thereof;

FIG. 5 is a top plan view thereof;

FIG. 6 is a left side elevational view thereof; and,

FIG. 7 is a rear elevational view thereof.

FIG. 1

FIG. 2

FIG. 3

FIG. 4

FIG. 5

FIG. 6

FIG. 7
